UNITED STATES PATENT OFFICE.

HARRY ROBERT NORTHOVER, OF WINNIPEG, MANITOBA, CANADA.

MACHINE FOR FILLING CARTRIDGE-MAGAZINES, CARTRIDGE-BELTS, STRIP-CHARGERS, AND THE LIKE.

1,395,928.

Specification of Letters Patent. Patented Nov. 1, 1921.

Application filed March 5, 1918. Serial No. 220,667.

To all whom it may concern:

Be it known that I, HARRY ROBERT NORTHOVER, a subject of the King of Great Britain, and resident of Winnipeg, Manitoba, 5 Dominion of Canada, have invented certain new and useful Improvements in Machines for Filling Cartridge-Magazines, Cartridge-Belts, Strip-Chargers, and the like, of which the following is a specification.

10 This invention has reference to machines or appliances for filling the cartridge belts and strip-chargers of machine guns, and for transferring or feeding cartridges from a hopper or the like into machine-gun and 15 similar cartridge receptacles and cartridge containers generally, other than the rotary pan or drum-type magazines used in connection with the Lewis gun.

In all mechanical belt-filers and other 20 machines for loading or filling cartridges into strip-chargers, magazines and the like, it is most essential to avoid "blanks" or unfilled cartridge-pockets or cartridge-receptacles, as if a belt, strip or magazine is 25 fed into or applied to a machine or automatic gun with any pocket or receptacle not containing a cartridge, a stoppage in the automatic firing action of the said gun will occur wherever the "blank" or unfilled 30 pocket or the like exists. It will also be realized that when belts, charger-strips or magazines are filled mechanically, "blanks" such as above referred to would be caused if, on a pocket or cartridge receptacle being 35 brought to the cartridge-receiving position, the cartridge-feed device of the machine failed to introduce a cartridge into the said pocket or receptacle and this failure in the cartridge-feed was followed by a movement 40 of the belt, strip or magazine such as would take the unfilled pocket or receptacle thereof away from the said cartridge-receiving position and brings the next pocket or receptacle into alignment with the feed device.

45 In the specifications of my applications for Letters Patent Serial Nos. 176863 and Number 220,666, I described, in its application to machines for filling the rotary pan or drum-type magazines of the Lewis gun, 50 means for positively preventing the occurrence of "blanks" in Lewis magazines, consisting of an automatic stop mechanism which governs or controls the alternating operations of the cartridge-feed and pan- 55 feed mechanisms of the machine in such a

way that it is only possible for the pan to be fed around or rotated after the cartridge-feed mechanism has operated properly to introduce a cartridge into the magazine, whereas if any conditions should arise 60 or be set-up within the machine that would prevent a cartridge being so inserted, then the stop mechanism operates automatically and immediately to arrest the working of the machine and prevent any movement of the 65 magazine that would take the unfilled cartridge-space away from or beyond the cartridge-receiving position.

The object of the present invention is to 70 obviate the occurrence of "blanks" in connection with the mechanical filling of the machine-gun belts, strip-chargers and cartridge-magazines or receptacles generally (other than Lewis-gun magazines), and this 75 object I propose to attain by the mechanism hereinafter described and pointed out in the appended claims.

The present invention is capable of application to any kind of machine for filling belts, strip chargers and magazines of the 80 description herein specified, but I propose, by way of example, to describe the same in its application to a machine-gun belt-filling machine in which the cartridges are fed or forced endwise (bullet-end first) from a 85 hopper or like receptacle into the pockets or clips of the belt; the cartridge-feed device of the said machine consisting of a reciprocating plunger or slide which in practice is geared to the mechanism or device that gives the feed movement to the belt after each cartridge-inserting operation of the plunger.

Figure 1 is a sectional elevation of a part 90 of a belt-filling machine of the above-mentioned type, showing the manner in which an automatic stop mechanism may be applied thereto in accordance with the present invention.

Fig. 2 is a sectional elevation of the stop 100 mechanism separately; the parts being shown in the positions in which they are held by cartridge weight so long as the machine is functioning normally.

Fig. 3 is a similar view to Fig. 2, but 105 shows how the mechanism locks the cartridge-feed plunger when there are no cartridges in the hopper.

Fig. 4 is a plan of the said stop mechanism.

The same letters of reference indicate corresponding parts in the several figures of the drawings.

In Fig. 1, I have shown only the cartridge-supply hopper a , the cartridge-inserting plunger b and the automatic stop mechanism, since the arrangements for guiding the belt in front of the hopper outlet a^1 , for giving the intermittent feed movement to the said belt, and for locking the belt with a pocket in alignment with the said outlet a^1 during the cartridge-inserting operation of the plunger (which are not illustrated in the drawings) may be of any suitable or convenient kind, such as commonly used in machines of this character.

The plunger b works in suitable guides on the bed-plate b^1 , and it is driven or reciprocated in any convenient manner, while the cartridge-hopper is arranged so that it will deliver cartridges successively into the path of the said plunger and provide for the said cartridges being forced, by the forward stroke of the plunger, endwise (bullet first) through the hopper-outlet into the pockets of the belt.

The stop mechanism for preventing "blanks" in filling, together with the means for governing or controlling same, are so constructed, arranged and timed to operate that the stopping of the working in the event of a cartridge failing to position itself in the path of the feed plunger can only occur at one particular point in the cartridge and belt-feed cycle, viz., at the instant when the belt-feed device has completed the movement that brings the next empty pocket into register with the hopper-outlet and the plunger is due to commence its cartridge feed point stroke; the object of this timing of the stop action being to insure that, when the said stop device is disengaged to allow the machine to resume working, all the parts shall be correctly positioned for effecting the feed of a cartridge into the said empty pocket during the first motion of the machine.

The stop mechanism embodied in the machine shown in the drawings is carried on the inside of a bracket-plate b^1 which is suitably supported on the base of the machine and upon which the plunger b reciprocates. It comprises a system of counterweighted levers, viz., a control lever j^3 and a plunger-stop lever j^4 , the lever j^3 comprising two parallel side plates disposed externally of the lever j^4 , as shown in Fig. 4 and being pivotally hung from a bracket j^{10} attached to the inside of the plate b^1 , the end farthest from the hopper carrying the counterweight j^5 , while its hopper end is furnished with a cartridge contact piece j^6 that is located in a hole in the slide plate b^1 immediately underneath the bottom of the hopper. This arrangement provides that as each successive cartridge drops from the hopper into its feed

position between the hopper-outlet and the plunger, it rests upon the contact j^6 as shown in dotted lines in Fig. 2.

The plunger-stop lever j^4 is located between the side plates of the control lever j^3 , and is independently pivoted on a hanger j^{11} inward of the control lever bracket j^{10} . Its rear extremity is loosely pivoted at j^9 to the counterweight end of the control lever, while its forward part carries a plunger-stop j^{20} , disposed in another opening j^{22} that is formed in the bracket-plate b^1 at some distance inward of the cartridge contact j^6 .

The distance between the centers of the cartridge contact j^6 and the plunger stop j^{20} is less than the length of the stroke of the plunger, and the relative dispositions of the parts b , j^6 , j^{20} , are such that, during the greater portion of its reciprocation, the said plunger is riding either over the contact j^6 and the stop j^{20} , or over the stop only, and this renders it impossible for j^6 or j^{20} to be lifted or made to project over the top of the plate b^1 by the action of the counterweight on the two levers, but as the plunger comes to the end of its idle or return stroke, it entirely clears the stop j^{20} , with the result that the stop mechanism is freed of the restraint previously exerted thereon by the plunger. The movement of the plunger beyond the stop j^{20} coincides with the completion of the feed movement of the belt under the action of the belt-feed device, and provided that at this moment there are cartridges in the hopper ready to fall, the bottom cartridge drops into the feed position on top of the control-lever contact j^6 , when the weight of the cartridges bearing on said contact will counterweight the tendency of the counterweight to lift the plunger stop and the continued rotation of the operating crank of the machine will impart the working or feeding stroke to the plunger and the said bottom cartridge will be fed or thrust into the pocket of the belt that is then in register with the hopper-outlet, and as the plunger advances it rides first over the stop j^{20} and then over the contact j^6 so that before the cartridge weight is taken off the control lever by the plunger working under the pile of cartridges in the hopper, the stop mechanism is already under the restraint of the said over-riding plunger and so cannot possibly operate to arrest the working of the machine.

If, however, at the moment when the plunger slides clear of the stop j^{20} , there is not a sufficient weight of cartridges ready to fall on to the control lever contact and overcome the counterweight, then the said counterweight immediately takes control and by oscillating the levers j^3 , j^4 , lifts the stop j^{20} into the path of the plunger as shown in Fig. 3, and also causes the cartridge contact to project upon the surface of the bracket-plate j^2 . This locks the plun-

ger in the position shown in Fig. 3 and renders it impossible for the continued rotation of the driving crank to impart a useless or non-effective forward movement to the plunger, and as the belt-feed device is geared to, or worked from the same operating mechanism as, the cartridge feeder, it follows that the locking or arresting of the plunger simultaneously and positively locks the belt-feed device and thus prevents any movement being imparted to the belt that would result in a "blank" or unfilled pocket in the same.

10 The stop mechanism automatically liberates or releases the cartridge-feed and belt-feed immediately a sufficient weight of cartridges falls onto the control lever contact j^s to overcome the counterweight, when the resultant oscillation of the levers removes the plunger stop from the path of the plunger and leaves the said feed device free to carry on its respective functions on rotation of the operating handle being resumed.

15 The application of my invention to machines for feeding cartridges endwise into the clips of machine-guns, strip-chargers, and also to machines for feeding cartridges endwise or sidewise into the cartridge magazines or cartridge feeding receptacles of 20 machine and automatic guns (other than the magazines of the Lewis automatic gun) differs in no essential respect from its application to machines for filling machine-gun belts as herein described.

25 35 I wish it to be understood that the manner of arranging or applying the stop mechanism to such machines may be varied or modified as may be desired to suit or adapt the same to the particular kind of cartridge 40 feeding or cartridge-inserting devices or mechanism that is embodied in the said machine; and, further, instead of arranging the stop mechanism so that it will function directly to lock the cartridge-feed device as

in the particular machine above described, it 45 may, in some cases, be arranged to act on the belt, strip or magazine feeder, or on the operating mechanism or device from which the cartridge and belt, or their feeder, obtain their alternating movements. 50

Having described my invention, what I claim and desire to secure by Letters Patent is—

1. In an automatic stop mechanism for cartridge-feeding machines, the combination with a cartridge-feed device, and a hopper or guide down which the cartridges are fed by gravity into the range of action of said device, of a system of counterweighted levers normally restrained by the cartridges, and a member controlled by said levers and locking the feed device in the event of a cartridge failing to position itself before said feed device. 55

2. A machine of the character described 60 comprising a cartridge-feed device, a hopper or guide down which the cartridges are fed by gravity into the range of action of said device, a counterweighted control lever normally restrained by the cartridges that fall 70 to the feed position, and a stop-lever actuated by the control lever and having means for automatically locking the feed-device when said levers are released from restraint. 75

3. In machines of the character described, 80 the combination with a reciprocating plunger and a hopper down which cartridges are fed into the range of action of said plunger, of a counterweighted control-lever normally restrained by the cartridges, and a lever 85 controlled by the counterweighted lever and having a stop adapted to be projected into the range of action of the plunger when the counterweighted lever is released from restraint.

In testimony whereof I have signed my name to this specification.

HARRY ROBERT NORTHOVER.
